CLAIM

The ornamental design for a swim vest as shown and described.

DESCRIPTION

FIG. 1 is a front, left, and top perspective view of the swim vest, showing my design;

FIG. 2 is a rear, right, and bottom perspective view thereof;

FIG. 3 is a front, right, and bottom perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is an enlarged view of an encircled area labeled "9" in FIG. 1.

The broken lines depict environmental subject matter only and that form no part of the claimed design. The dot-dash broken lines shown in FIGS. 1 and 9 framing portions of the swim vest for enlargements purposes form no part of the claimed design.
